UNITED STATES PATENT OFFICE.

EUGÈNE SCHNEIDER, OF PARIS, FRANCE, ASSIGNOR TO SCHNEIDER & CIE., OF PARIS, FRANCE, A LIMITED JOINT-STOCK COMPANY OF FRANCE.

TRANSPORT APPARATUS FOR DEMOUNTING AND REMOUNTING GUN-BARRELS.

1,345,892.

Specification of Letters Patent.

Patented July 6, 1920.

Application filed March 31, 1919. Serial No. 286,487.

To all whom it may concern:

Be it known that I, EUGÈNE SCHNEIDER, citizen of the French Republic, and a resident of 42 Rue d'Anjou, Paris, France, have **5** invented a new and useful Transport Apparatus for Demounting and Remounting Gun-Barrels, which invention is fully set forth in the following specification.

This invention has for its object to **10** provide an improved form of the apparatus for removing a gun barrel from its mounting for the purpose of transport, and for replacing it upon its mounting, constituting the subject matter of our invention for **15** which a patent was applied on March 31, 1919, Serial No. 286,486.

The improved form of apparatus according to the present invention is illustrated in the accompanying drawings in which:—
20 Figure 1 is a longitudinal elevation of the present improved apparatus, showing one stage of the removing or replacing operation.

Fig. 2 is a similar elevation showing another stage of the operation.

Fig. 3 is a cross section on the line III—
III of Fig. 2.

Fig. 4 is a plan, drawn to a smaller scale, showing in full lines the gun in the firing **30** position, and showing in dotted lines the gun barrel removed from the mounting after it has been rotated together with the fore axle, on a supporting jack into such a position as will allow the placing of the rear axle in order to receive the breech of the gun barrel as the latter is demounted from its carriage, or in order to move the rear axle into position for the purpose of replacing the gun barrel upon the mounting.

40 The same figure shows in dot and dash lines the gun barrel with the fore axle and the gun mounting platform brought into line behind one another for the purpose of removing the gun barrel from or replacing it upon the mounting.

As in the construction described in my copending application, hereinbefore referred to the present improved apparatus for transporting the gun barrel and for **50** placing it upon its mounting, comprises a wheeled fore axle A—B, on the coupling pin of which a collar composed of two parts E—F is adapted to pivot and form bearings for the chase G of the gun barrel, between

two ribs g formed on the latter. This **55** wheeled fore axle is always combined with a wheeled rear axle H comprising a supporting cradle which is adapted to fit between two flanges g¹ formed on the gun barrel G¹ a suitable distance forward of the gun breech. **60**

The present improved apparatus for removing the gun barrel from the mounting and placing the gun barrel upon the transport vehicle, and reversely, for replacing the gun barrel upon the gun carriage, comprises **65** as in the constructional example described in said copending application, removable slide tracks Q hinged at their rear ends R to the gun cradle L.

According to the present invention, these **70** slide tracks when placed on the cradle, are always held in the prolongation of the slide-ways of the gun cradle, both for the purposes of removal and replacement. With this object they may be connected to the **75** gun carriage frame N by stays Q¹ consisting for instance of connecting rods jointed at their ends respectively to the tracks Q and the carriage frame N.

The removable tracks Q, thus fixed in **80** place, are combined with an independent jack Z placed underneath the gun barrel at a register mark G² marked on the gun barrel near the center of gravity of the combined gun barrel and wheeled fore axle **85** A—B; a slight preponderance being allowed to the forward portion connected to the fore axle. The cross-head Z² of the jack Z forms a footstep bearing for the pivot pin g³ (Fig. 3) of a cradle G³ serving to carry the gun **90** barrel.

When the gun in any firing position is situated behind a covering mass, such as the position shown in full lines in Fig. 4, the gun barrel with the carriage frame N, can be **95** readily rotated on the lower platform O in order to bring them into a position (shown in dot and dash lines in Fig. 4) where it is possible to move the gun barrel forward for the purpose of removing it from the gun **100** carriage.

Then for effecting the removal, the wheeled fore axle on the one hand and the independent jack Z on the other hand are placed at the desired points in the vertical **105** axial plane of the gun barrel. The gun barrel is slid along the removable tracks Q until the chase rests in the divided collar

E—F of the fore axle as shown in Fig. 1. Then the jack Z is brought as exactly as possible under the register mark G² and is then raised so as to constitute a support for the 5 gun barrel. The stays Q¹ can then be removed and the removable tracks Q can be let down out of the way. From this moment onward the combined gun barrel and wheeled fore axle can be lifted without effort, and the combination can be rotated 10 horizontally into any position where there is sufficient room for bringing up the wheeled rear axle conveniently.

To complete the formation of the transport vehicle, it is merely necessary to operate the jack in such a manner as to lower the gun barrel on to the wheeled rear axle.

The replacing of the gun barrel upon the gun carriage is effected by reversing the 20 above described sequence of operations. The independent jack Z is placed underneath the register mark G²; the gun barrel is slightly raised in order to disengage it from the wheeled rear axle; and then the combined 25 gun barrel and fore axle are rotated horizontally on the jack, and the gun carriage and the carriage frame N are rotated horizontally on the platform O, so as to bring the gun barrel and the gun carriage axially 30 in line with each other (position indicated in dot and dash lines in Fig. 4).

It is preferred that the independent jack shall have the form shown in the drawings, that is to say, that it shall be constructed, 35 as shown in Fig. 3, of two jacks Z, Z, mounted on a common bedplate Z¹ and interconnected by a cross-head Z². This cross-head is formed at its center with a footstep bearing for the pivot pin g³ of a cradle G³ 40 for supporting the gun barrel.

What I claim is:—

1. In transport apparatus for demount-

ing and remounting gun-barrels, the combination of independently movable fore-wheeled and rear-wheeled axles placed to receive successively and respectively the chase and breech of the gun-barrel as the latter is slid from its carriage, a pivoted collar forming a seat on the fore-wheeled axle for the chase and permitting angular horizontal 45 movement of the gun-barrel relative to the fore-wheeled axle, a lifting-jack placed beneath the gun-barrel and coacting with the fore-wheeled carriage to support the gun-barrel during the placement of the rear-wheeled axle preliminary to receiving the breech of the gun-barrel subsequently lowered thereon by the lifting-jack, and a cradle pivoted on the lifting-jack to form a 50 seat for the gun-barrel and to permit horizontal angular movement of the gun-barrel relative to the lifting-jack.

2. In transport apparatus for demounting and remounting gun-barrels, the combination of independently movable fore-wheeled 55 and rear-wheeled axles placed to receive successively and respectively the chase and breech of the gun-barrel as the latter is slid from its carriage, a lifting-jack placed beneath the gun-barrel and coacting with the 60 fore-wheeled axle to support the gun-barrel during the placement of the rear-wheeled axle preliminary to receiving the breech of the gun-barrel subsequently lowered thereon by the lifting-jack, and a cradle pivoted on the lifting-jack to form a seat for the gun-barrel and to permit horizontal angular movement of the gun-barrel relative to the lifting-jack.

In testimony whereof I have signed this 80 specification.

EUGÈNE SCHNEIDER.
